(57) CLAIM

The ornamental design for putter golf club head, as shown and described.

DESCRIPTION

FIG. 1 is a perspective bottom plan view of a putter golf club head showing my design;

FIG. 2 is a top plan view thereof;

FIG. 3 is a bottom plan view thereof;

FIG. 4 is a rear elevational plan view thereof;

FIG. 5 is a front elevation view thereof;

FIG. 6 is a heel end view thereof;

FIG. 7 is a toe end view thereof;

FIG. 8 is a perspective bottom view of a putter golf club head in accordance with a second embodiment of my invention showing my design;

FIG. 9 is a top plan view of the putter golf club head shown in FIG. 8;

FIG. 10 is a bottom plan view of the putter golf club head shown in FIG. 8;

FIG. 11 is a rear elevational plan view of the putter golf club head shown in FIG. 8;

FIG. 12 is a front elevation view of the putter golf club head shown in FIG. 8;

FIG. 13 is a heel end view of the putter golf club head shown in FIG. 8; and,

FIG. 14 is a toe end view of the putter golf club head shown in FIG. 8.

The broken lines shown are included for the purpose of illustrating unclaimed subject matter and form no part of the claimed design.

1 Claim, 10 Drawing Sheets
